UNITED STATES PATENT OFFICE.

JAMES A. SHARP, OF SPRINGFIELD, OHIO, ASSIGNOR, BY MESNE ASSIGNMENTS, TO
INTERNATIONAL HARVESTER COMPANY, A CORPORATION OF NEW JERSEY.

BALING-PRESS.

1,308,645.

Specification of Letters Patent.

Patented July 1, 1919.

Application filed August 28, 1916. Serial No. 117,354.

To all whom it may concern:

Be it known that I, JAMES A. SHARP, a citizen of the United States, residing at Springfield, in the county of Clark and State of Ohio, have invented certain new and useful Improvements in Baling-Presses, of which the following is a full, clear, and exact specification.

This invention relates to baling presses, and more particularly to block case operating mechanisms therefor.

One of the objects of this invention is to simplify and improve the block case operating mechanism.

Another object of the invention is to simplify and improve the control of the block case operating mechanism.

Another object is to provide a baling press having block case operating mechanism adapted to meet all the requirements for successful commercial operation.

These and other objects are accomplished by providing in a baling press a block case, improved operating mechanism for actuating the same, and improved control means associated with the block case and actuating means.

The invention is illustrated on the accompanying sheets of drawings, in which—
Figure 1 is a fragmentary side elevation of a hay press embodying my invention, the feeder head being shown in its lowered position after having released the block from the casing to permit the same to fall into the compression chamber, the other parts being in corresponding positions;

Fig. 2 is a fragmentary side elevation of the same hay press with the feeder head in its raised position and the other parts in their corresponding positions;

Fig. 3 is a fragmentary elevation of the feeder head and operating parts associated therewith as viewed from the right in Fig. 2;

Fig. 4 is a detail plan view, the parts being in section, of the block containing casing, guide and push rods and other parts associated therewith;

Fig. 5 is an end elevation of the same;

Fig. 6 is a detail view of the operating and control parts as they appear when the feeder head is in a raised position and the control lever has been operated to place the block casing into gear; and

Fig. 7 is a similar detail view showing the manner in which the actuating mechanism and block case are automatically thrown out of gear with each other.

The various novel features of my invention will be apparent from the following description and drawings and will be particularly set forth in the appended claims.

The hay press 10 here shown, in general, includes the frame structure forming a compression chamber 11 and a baling chamber 12, there being a compression plunger 13 reciprocated in the compression chamber from any suitable source through a link 14. The feeder head 15 receives its motion by a connection from the compression plunger including a link 16, arm 17, shaft 18, on which is mounted an arm 19, connected to a link 20, a suitably supported bell crank 21, a link 22 between the bell crank 21 and an arm 23 mounted upon one end of a rock shaft 24, upon which is secured a casting 25 connected to the main arm 26 of the feeder head 15. This feeder head is pivoted intermediate its ends to one end of the arm 26, and in order to prevent injury to the feeder head or co-operating parts if the feeder head should strike an unyielding obstruction, the arm 26 and the casting 25 are yieldably connected together by the usual spring and bolt arrangement 28 associated with such parts.

Secured to the main frame of the press on opposite sides thereof are two vertically arranged supporting members 29 and 30, the upper ends of which are bent over and secured to the upper bent portions of two other supporting members 31 and 32, which also are secured to the main frame of the press. The supporting members 29 and 30 are connected by a cross bar 33, and the frame members 31 and 32 are connected by a similar cross bar 34, both of which are provided with apertures through which horizontal portions of guide rods 35 and 36 slide. The vertical

portions of these guide rods are secured by suitable clips 37 and 38 to a block case 39 for the reception of a block 40, which is yieldingly retained therein by spring-pressed straps 41 of the block case, which straps terminate in offset tip portions 42 engaging a lower edge of the block 40. The block 40 is normally supported on a suitable table 43, from which the casing and block are pushed laterally when the block case operating mechanism is thrown into gear. Secured to and connecting the guide rods 35 and 36 is an adjustable bracket 44 having a passageway 45 extending therethrough, and in this passageway there being located a shoulder 46 which is adapted to be engaged by one end of a push rod 47, the other end of which is pivoted to one end of a rocker arm 48 pivoted in a bracket 49 secured to the cross bar 33. The other end of the rocker arm 48 is provided with a roller 50, which under certain conditions is held in contact with a hook-shaped cam 51 connected to the feeder head arm 26 and receiving its motion from the rock shaft 24. A spring 52 connects the upper part of the rocker arm 48 to the block case in a manner such that the spring tends to hold the block case on the table 43 or to pull it back onto such table when removed therefrom, the spring 52 also tending to hold the roller 50 against the cam 51 and further to draw the push rod 47 into a position where it may pass into engagement with the shoulder 46 when the block case mechanism is thrown into gear.

A control member 53, having arms 54 on opposite sides of the machine, has a horizontally arranged portion 55 (see Fig. 3) journaled in suitable bearings 56 secured to the frame members 29 and 30. Secured to the horizontal portion 55 of the control member is a casting having two offset projections 57 and 58, respectively, the first projection 57 when in one position, as shown in dotted lines in Fig. 2, engaging a shoulder portion 59 of the push rod 47 to hold the push rod up out of engagement with the shoulder 46 of the bracket 44. In other words, the projections 57 in the position shown in dotted lines in Fig. 2, holds the block case operating mechanism out of gear with the block case. However, when the control lever 53 is thrown forwardly from the position shown in Fig. 2 to the position shown in Fig. 55 1, the projection 57 is lowered to permit the push rod 47 to fall into a position on a level with the shoulder 46; or, in other words, to permit the block case operating mechanism to be thrown into gear. When the control member 53 is thrown forwardly into operative position, the other projection 58 (see Fig. 6) is thrown under a hook portion 60 of a leaf spring 61 secured to the bracket 44,

whereby the control lever is yieldingly retained in such position and the latch 57 is 65 yieldingly locked against throwing the push rod 47 out of engagement with the shoulder 46; or, in other words, to prevent the projection 57 from throwing the block case operating mechanism out of gear. The spring 61 70 also serves another function, and that is to automatically throw the block case operating mechanism out of gear when the block case 39, guide rods 35 and 36, bracket 44, and spring 61 are on their return movement, as 75 shown in Fig. 7.

To insure safe operation of the parts, it is necessary that the block 40 be placed in its case with a reasonable degree of accuracy; that is to say, the block must be placed substantially in the center of the case. The block may be inserted from either side by depressing one or the other of two weighted members 62, pivotally connected to the side frame members 31 and 32, and sliding the 85 block until it strikes the other of said members. The block may then be locked in the case against lateral movement by the horizontally arranged portions of the weighted member 62. If the weighted portion of one 90 of the members 62 is lifted, it may act as signal that the block is not properly placed wholly within the case. A careless operator may not place the block wholly within the case and may not pay any attention to the 95 position of the weighted member 62. However, if the block extends laterally out of the case, it will be impossible to throw the operating mechanism into gear because of the fact that one or the other of two longitudinally extending spaced rods 63 connected to the arms 54 of the control lever 53 will pass into engagement with the block, as shown in Fig. 4. Therefore, in order to throw the operating mechanism into gear, it is necessary 100 that the block be properly placed in the case. In this manner no injury can be done to the machine by improper placing of the block within the case.

Normally the block case operating mechanism is out of gear for about twelve to fifteen cycles of the feeder head. As shown in Fig. 2, the operating mechanism is out of gear. To throw it into gear, it is merely necessary to throw the lever 53 forwardly 115 or toward the block case. If the block is properly set in the case, the rods 63 will pass on opposite sides of the block to permit the actuating means and associated parts to be thrown into gear, and, as above stated, 120 if the block is not centrally set, one of these links will pass into engagement with the block to prevent the case operating mechanism from being thrown into gear. When the lever is thrown toward the block case, 125 with the feeder head 15 completely raised,

as shown in Fig. 2, the projection 57 permits the push rod 47 to fall into a position where it may pass into engagement with the shoulder 46 on the guide rod bracket 44, and the other projection 58 passes under the leaf spring 61 to yieldingly hold the lever 53 in its operative position. At the same time the spring 52 will draw the roller 50 into contact with the cam 51 and will draw the push rod 47 into a position to positively insure its passage into engagement with the shoulder 46. Now, if the feeder head 15 is lowered, the cam 51 will rock the rocker arm 48 to actuate the push rod 47 which is effective in pushing the case and block away from the table 43 and into a position where an arm 64 on the feeder head may force the block out of the case. As the case is moved away from the table 43, the case returning spring 52 is placed under added tension. This spring 52 returns the case toward its normal position as the cam 51 permits same. Just as the cam 51 passes away from the roller, as shown particularly in Fig. 7, the leaf spring 61 on the guide rod bracket 44 pushes the projection 58 in a manner to automatically lift the projection 57 to raise the push rod 47 out of engagement with the shoulder 46 and to push the control lever 53 to its initial inoperative position; that is to say, the case operating mechanism is automatically thrown out of gear. With the case operating mechanism out of gear, the feeder head 15 continues as usual on its next down feeding stroke, and of course, the cam 51 actuates the push rod forward again, but, being out of gear, the rod does not actuate the case. It merely slides through the passageway 45 above the bracket shoulder 46. This time on its forward stroke the push rod 47 also rides over the projection 57 until the shoulder in the push rod hooks over the projection 57, so that as the feeder head now rises, the roller 50 will not follow the cam 51, even under the tension of the spring 52; that is to say, the push rod 47 is hooked up. Under these conditions, during the next twelve or fifteen strokes, while the block case is at rest, there will be no wear between the cam and roller. The case will not be actuated again until the lever 53 is thrown manually to place the case operating mechanism into gear. As soon as the lever 53 is thrown forwardly, the spring, which is under tension, will again throw the roller into contact with the cam, and if the feeder head is raised, will throw the push rod 47 into operative engagement with the shoulder on the guide rod bracket 44 for actuating the case on the next downward movement of the feeder head 15.

It is evident that there may be various modifications of the invention as herein particularly shown and described, and it is my

intention to cover all such modifications which do not involve a departure from the spirit and scope of the invention as set forth in the following claims.

What I claim as new is:

1. In a baling press having a frame, the combination of a block case, actuating means, means carried by the frame, operable by the actuating means and intermittently engageable with said block case to move said block case to block setting position.

2. In a baling press having a frame, the combination of a block case, actuating means, and a reversible connecting member carried by said frame, operable by said actuating means and intermittently engageable with said block case to move said case to block setting position.

3. In a baling press having a frame, the combination of a block case, actuating means, and a controlled reversible connecting member carried by the frame, operable by said actuating means and intermittently engageable with said block case to move said block case to block setting position.

4. In a baling press having a frame, the combination of a block case, actuating means, connecting means carried by the frame, operable by said actuating means and intermittently engageable with said block case to move said case to block setting position, and a control member for said connection.

5. In a baling press having a frame, the combination of a block case, means for actuating the same, a connection therebetween carried by the frame and intermittently engageable with said block case for transmitting motion to the block case, means for moving said connection into an operative position, and means for moving said connection into an inoperative position.

6. In a baling press having a frame, the combination of a block case, means for actuating the same, a connection therebetween carried by the frame for transmitting motion to the block case, means for moving said connection into an operative position, and means for automatically moving said connection into an inoperative position.

7. In a baling press, the combination of a block case, actuating means therefor, a member for transmitting motion from said means to said block case and movable with respect thereto, means for holding said member in inoperative position, and means for actuating said last mentioned means to permit said member to move into operative position.

8. In a baling press, the combination of a block case, actuating means therefor, a member for transmitting motion from said means to said block case, means for holding said member in inoperative position, control means for actuating said last mentioned

means to permit said member to move into operative position, and means for retaining said control means in one of its positions.

9. In a baling press, the combination of a block case, actuating means therefor, a reciprocable motion transmitting member therebetween, means for holding said member in an inoperative position, and means for releasing said member from said holding means to permit it to move into operative position.

10. In a baling press, the combination of a block case, actuating means therefor, a longitudinally movable motion transmitting member therebetween, means for holding said member in an inoperative position, means for releasing said member from said holding means to permit it to move into operative position, and means for automatically moving said member back into an inoperative position.

11. In a baling press, the combination of a block case, actuating means therefor, a motion transmitting member therebetween whereby said case may be moved from its normal position, said member being capable of relative bodily movement with respect to said block case, and means whereby said case is automatically returned to its normal position and said transmission member is moved into an inoperative position.

12. In a baling press, the combination of a block case, actuating means therefor, a motion transmitting member connected therebetween and movable with respect to said case, means for holding said member in contact with said actuating means under certain conditions, and means for holding said member out of engagement with said means under other conditions.

13. In a baling press, the combination of a block case, means for actuating the same, a member associated with said actuating means, and a second and adjustable member connected to the first member for completing an operative connection between the actuating means and the block case.

14. In a baling press, the combination of a block case, an actuating cam, a pivotally mounted member actuated by said cam, a second member connected to said first member and completing an operative connection between said cam and said case, and a connection between said first member and case for holding said first member in contact with said cam.

15. In a baling press, the combination of a block case, an actuating cam, a pivotally mounted member actuated by said cam, a second member connected to said first member and completing an operative connection between said cam and said case, a connection between said first member and case for holding said first member in contact with said

cam, and controlled means associated with one of said members.

16. In a baling press, the combination of a block case, a cam for actuating the same, a pivotally mounted member normally out of engagement with said cam, means under certain conditions for holding said member in contact with said cam, and a second member connected with the first member to complete an operative connection between said actuating cam and block case.

17. In a baling press, the combination of a block case, a cam for actuating the same, a pivotally mounted member normally out of engagement with said cam, means under certain conditions for holding said member in contact with said cam, a second member connected with the first member to complete an operative connection between said actuating cam and block case, and means for normally holding said second member in an inoperative position.

18. In a baling press, the combination of a block case, a cam for actuating the same, a pivotally mounted member normally out of engagement with said cam, means under certain conditions for holding said member in contact with said cam, a second member connected with the first member to complete an operative connection between said actuating cam and block case, means for normally holding said second member in an inoperative position, and means for moving said second member into operative position.

19. In a baling press, the combination of a block case, actuating means therefor, connecting means therebetween normally held in inoperative position, means for releasing said connecting means whereby it may move into operative position whereupon the case is moved from its normal position, means for returning said case to its normal position, and means for moving said connecting means into inoperative position.

20. In a baling press, the combination of a block case, actuating means therefor, connecting means therebetween normally held in inoperative position, means for releasing said connecting means whereby it may be moved into operative position whereupon the case is moved from its normal position, means for returning said case to its normal position, means for moving said connecting means into inoperative position, and means for holding said connecting means in such inoperative position.

21. In a baling press, the combination of a case for the reception of a block, means for actuating the case, and control means whereby said case may be actuated only when the block is properly positioned in the case.

22. In a baling press, the combination of a case for receiving a block, actuating means therefor, and control means whereby said

actuating means and case are held out of actuating relationship unless the block is properly placed within the case.

23. In a baling press, the combination of a case for the reception of a block, actuating means therefor, a connection between said means and case, and means whereby said connection is withheld from an operative position unless the block in the case is prop-
10 erly set.

24. In a baling press, the combination of a case for the reception of a block, members to prevent lateral displacement of a block from the case, actuating means for said case, and a controlled connection between said case 15 and actuating means whereby the case will be actuated only when the block is properly retained in the case by said members.

In testimony whereof I affix my signature.
JAMES A. SHARP.
